UNITED STATES PATENT OFFICE.

OSWALD C. BREWSTER, OF CASPER, WYOMING, ASSIGNOR TO STANDARD OIL COMPANY, OF WHITING, INDIANA, A CORPORATION OF INDIANA.

ART OF CONVERTING HYDROCARBON OILS.

Application filed June 20, 1925. Serial No. 38,513.

- The present invention relates to improvements in the art of converting hydrocarbon oils, and will be fully understood from the following description, illustrated by the accompanying drawing, in which apparatus for carrying the invention into effect is diagrammatically illustrated. The apparatus is described and claimed in a co-pending application, Serial No. 38,514.
- 10 Referring more particularly to the drawings, the numeral 5 indicates the still or chamber, preferably lagged, in which the conversion operation takes place. From this still, vapors pass through a line 6 to a suitable stripping column 7, in which they are stripped of their heavier fractions by being intimately contacted with fresh oil supplied to the system, as hereinafter more fully set forth. From the stripping column 7, vapors pass through the line 8 to a condenser 9, and the condensate and cool vapors pass from the latter through the line 10 to a receiving drum 11. From the receiving drum condensate may be discharged through the line 12 controlled by valve 13^a and uncondensed gases are discharged through the line 13 controlled by valve 14. Air or other oxidizing gas containing oxygen is supplied to the still from the main air supply line 15 through line 16 controlled by valve 17, and entering the lower portion of the still 5. As will be hereinafter more fully pointed out, the heat required for conversion of the oil in the still is supplied by internal combustion effected by means of 25 the air or oxygen supplied in this manner.
- Suitable means exteriorly of the still 5 are provided for bringing the contents of the still to a temperature at which active oxidation will take place. As shown in the drawing, oil may be withdrawn from the still through the line 18 by the pump 19 and forced through the externally fired heating coils 20. The heated oil is discharged from the coil 20 through lines 21 and 22, through 30 which it returns to the still 5.
- In beginning operation, the still 5 is filled with oil, and a circulation is established by means of the pump 19, through the externally fired coil or preheater 20 and back to the still until the oil has been brought to a suitable temperature, say 600 to 650° F. or higher, at which oxidation will begin on the supply of air to the still. When the oil in the still has reached a suitable temperature, air is 35 supplied through the line 16 and controlled by the valve 17 to maintain the desired temperature in the still.
- Means are provided for supplying oil to the still 5 after the operation of conversion by internal combustion has begun. In the 40 form of the invention illustrated, a feed pre-heater 23 is provided, suitably in the form of a column or tower containing bubble plates 24. Fresh oil is fed to the upper portion of this preheater column through the line 25, the preheater column having first been brought to a temperature at which active oxidation will spontaneously take place by the supply of heated oil thereto from the heating coil 20 through the lines 21 and 26, 45 the latter being controlled by the valves 27 and 28. Air from the main supply line 15 is supplied to the lower portion of the oxidizing preheater 23 through the line 29 controlled by valve 30, and entering the preheating column 23 near its base. The supply of air is controlled so that the oil entering through the line 25 is brought to a conversion temperature of, say, 650 to 720° or 50 higher while passing through the preheating column. The period during which the oil remains in the preheating column is so short that substantially no deposition of carbon can take place therein. The oil preheated in the column 23 is supplied to the stripping column 7 through the line 31, and passes through the stripping column countercurrent to the vapors issuing from the still through line 6. The vapors are thereby 55 stripped of their heavy ends, and the fresh oil, together with reflux, passes from the stripping column 7 through the line 32 into the still 5.
- The gas and vapors issuing from the preheating column 23 pass out through vapor line 33 into a condenser and cooler 34, from which the condensate and cooled gases pass to a drum 35. From this drum, condensate is 60 discharged through a trap line 36 to the line 25, through which it is caused to re-enter the preheating column 23 with the feed stock. Uncondensed gas and vapors pass out of the drum 35 through line 37, which connects with the gas line 13 leading from the distillate collecting drum 11. 65
- To illustrate the operation of the device, the still 5 is charged with the oil to be converted, say a crude residue of about 19 to 20° Baumé gravity, and is brought to a temperature of 650° or higher, say about 740° F., 70

by circulating the oil by means of pump 19 through the externally fired heating coil 20, the oil returning to the still through the lines 21 and 22. When the oil within the still has 5 been brought to the desired temperature, the flow of oil through the heating coil 20 is stopped, and air is supplied through the line 16. The supply of air is controlled to maintain the desired temperature, say 720 to 760° 10 F. within the still 5.

When the oil being circulated through the heated coil 20 has reached a temperature of 650° or higher, a part of this oil is diverted through the line 26 into the column 23, into 15 which air is supplied through the line 29, and controlled by the valve 30. The fresh oil to be supplied to the system enters the pre-heating column 23 through the line 25, and the supply of air to the preheating column 20 is controlled so that the oil reaches, in the base of the column, a predetermined temperature of 640° F. or higher, and preferably about 700 to 740° F. It is understood, of course, that the supply of oil through the line 25 25 from the fired coil 21 to the preheating column 23 is stopped when operation of the column in its proper manner begins.

At this stage of operation, the contents of the still 5 receive their entire heat from the 30 combustion of oil by controlled quantities of air admitted through the line 16. At the same time, the fresh stock to be supplied to the still 5 during operation is preheated, also by controlled oxidation, within the preheating column 23, from which it is discharged 35 as soon as it attains the desired temperature, the heated oil remaining in the preheating column 23 for an insufficient period of time to cause coke deposition therein to any substantial extent. The preheated oil from the 40 column 23 passes through the line 31 into the upper portion of the stripping column 7, through which it descends countercurrent through the vapors and gases rising from the still 5 through the line 6. In descending the 45 column, the feed stock causes some condensation of heavy ends of the vapors issuing from the still, and the condensate formed therein, together with the fresh oil pass through the line 32 into the still 5. The operation of feeding and conversion by controlled oxidation 50 within the still 5 are continued until the still is substantially filled with coke.

The vapors issuing from the column 7, 55 which have been deprived of their heavier ends, pass out through the line 8 and are condensed in the condenser 9. The condensate and uncondensed gases and vapors pass into the receiving drum 7, from which the 60 gases are discharged through the line 13.

In the preheating column 23, the air or other oxidizing gas introduced to effect pre-heating may cause a moderate amount of distillation. Substantially all the vapors 65 formed in the lower part of the column are

condensed by the cold feed stock supplied through the line 25. Any uncondensed portion passing out of the column 23 through the line 37 is condensed in the condenser 34 and discharged into the drum 35, in which uncondensed gases are separated and pass out through the line 37 to the gas line 13. The condensate collected in the drum 35 is discharged through the line 36 and enters the feed stock line 25, again entering the preheat- 75 ing column 23.

The entire system is maintained under a pressure of 4 to 5 atmospheres or higher. Suitable pressures may be, for example, from 100 to 300 pounds gauge. As already pointed out, the temperatures employed are in excess of about 650° F., and preferably about 720 to 760° F. Higher temperatures may be employed, if desired, for example, temperatures ranging to 850° F or higher. It is preferred, however, not to employ such higher ranges of temperatures, as the amounts of air or other oxidizing gas required to maintain them tend to cause excessive distillation of undesired heavy end products. 90

I claim:

1. The method of converting hydrocarbon oils which comprises maintaining a body of oil under pressure and at conversion temperature by internal oxidation within the body 95 of oil, removing vapors therefrom, heating a flowing stream of oil to conversion temperatures by supplying an oxygen containing gas in contact with said stream of oil, and passing said heated stream of oil before substantial conversion thereof into the body of oil. 100

2. The method of converting hydrocarbon oils which comprises maintaining a body of oil, circulating oil from said body in a confined stream through a heating zone and back 105 to said oil body until the oil body is brought to a temperature of active oxidation in the presence of an oxygen-containing gas, discontinuing said circulation of the oil, supplying into the body of oil controlled quantities 110 of oxygen-containing gas while maintaining upon the body of oil a pressure of at least four atmospheres, removing vapors evolved from the body of oil, and supplying to it additional oil preheated to approximately the temperature 115 of the body of oil.

3. The method of converting hydrocarbon oils which comprises maintaining a body of oil under pressure at conversion temperature 120 by supplying into said body of oil controlled quantities of oxygen containing gas, removing vapors evolved from the body of oil, pre-heating fresh oil to conversion temperatures, contacting the preheated fresh oil with the vapors evolved from said body of oil, and subsequently feeding it into said body of oil. 125

4. The method of converting hydrocarbon oils which comprises maintaining a body of oil under pressure and at conversion temperature by supplying controlled quantities of 130

oxygen-containing gas into the body of oil, bringing fresh oil to approximately the temperature of said body of oil by contacting it with an oxygen-containing gas in a body of heated oil, and delivering said fresh oil before substantial conversion thereof has taken place into said body of oil.

5. The method of converting hydrocarbon oils which comprises maintaining a body of oil under pressure at conversion temperature, bringing fresh oil to approximately the temperature of said body of oil by reacting thereupon with an oxidizing gas, and delivering said fresh oil before substantial conversion thereof has taken place into said body of oil.

6. The method of converting hydrocarbon oils which comprises maintaining a body of oil under pressure and at conversion temperature, removing vapors therefrom, bringing 20 fresh oil to approximately the temperature of said body by reacting thereupon with an oxidizing gas, bringing said fresh oil, before substantial conversion thereof has taken place, into intimate contact with the vapors 25 issuing from said body of oil, and, subsequently delivering the fresh oil into the latter.

7. The method of converting hydrocarbon oils into lower boiling hydrocarbon oils which comprises maintaining a body of oil under pressure and at conversion temperature by supplying controlled quantities of oxygen containing gas into the body of oil, bringing fresh oil to approximately the temperature of said body of oil by contacting it 35 with an oxygen containing gas, bringing the heated fresh oil, before substantial conversion thereof has taken place, into intimate contact with the vapors issuing from said body of oil, and subsequently delivering fresh 40 oil into the latter.

8. The method of converting hydrocarbon oils which comprises maintaining a body of oil under pressure and at conversion temperature, bringing a quantity of oil in a separate body to a temperature at which active oxidation will take place in the presence of an oxygen-containing gas, delivering fresh oil to said separate body of oil and simultaneously supplying an oxygen-containing gas 45 thereto in proportions to bring the fresh oil to conversion temperature within said separate body of oil, removing the heated oil from said separate body of oil before substantial conversion thereof has taken place, 50 and supplying it into the first mentioned body of oil.

9. The method of converting hydrocarbon oils into lower boiling hydrocarbon oils which

comprises maintaining a body of oil under pressure and at conversion temperature, 60 bringing a quantity of oil in a separate body to a temperature at which active oxidation will take place in the presence of an oxygen-containing gas, delivering fresh oil to said separate body of oil and simultaneously supplying an oxygen-containing gas thereto in proportions to bring the fresh oil to conversion 65 temperature within said separate body of oil, removing the heated oil from said separate body of oil before substantial conversion thereof has taken place, contacting the removed oil with vapors arising from the first mentioned body of oil, and subsequently supplying the fresh oil to the first mentioned 70 body of oil.

10. The method of converting hydrocarbon oils into lower boiling hydrocarbon oils which comprises maintaining a body of oil under pressure and at conversion temperature by supplying controlled quantities of oxygen-containing gas into the body of oil, bringing a quantity of oil in a separate body to a temperature at which active oxidation takes place 80 in the presence of an oxygen containing gas, delivering fresh oil to said separate body of oil and simultaneously supplying an oxygen-containing gas thereto in proportions to bring the fresh oil to conversion temperature within 85 said separate body of oil, removing the heated fresh oil from said separate body of oil before substantial conversion thereof has taken place, and supplying it to the first mentioned body of oil.

11. The method of converting hydrocarbon oils into lower boiling hydrocarbon oils 95 which comprises maintaining a body of oil under pressure and at conversion temperature by supplying controlled quantities of oxygen-containing gas into the body of oil, bringing a quantity of oil in a separate body 100 to a temperature at which active oxidation will take place in the presence of an oxygen-containing gas, delivering fresh oil to said separate body of oil and simultaneously supplying an oxygen-containing gas thereto in 105 proportions to bring the fresh oil to conversion temperature within said separate body of oil, removing the heated fresh oil from said separate body of oil before substantial conversion thereof has taken place, contacting said fresh oil with vapors arising from the first mentioned body of oil, and supplying the fresh oil subsequently to the first mentioned body of oil.
